UNITED STATES PATENT OFFICE.

FRANK L. FOSTER, OF CLEVELAND, OHIO, ASSIGNOR TO THE PHILIP CAREY MFG. CO.,
A CORPORATION OF OHIO.

COMPOSITE ROOFING.

1,230,396.

Specification of Letters Patent. Patented June 19, 1917.

Application filed April 6, 1915. Serial No. 19,609.

To all whom it may concern:

Be it known that I, FRANK L. FOSTER, a citizen of the United States, and a resident of Cleveland, county of Cuyahoga, State of Ohio, have invented certain new and useful Improvements in Composite Roofing, of which the following is a specification.

This invention relates to roofing and particularly to the type of roofing which is built into the building itself and comprises a continuous structure, as contrasted with roofs which comprise separate elements or sections which are previously prepared and positioned adjacent one another to form a roof having well defined joints between the sections thereof.

One object of my invention is to provide a roof having a gutter, which roof comprises a masonry foundation that may be monolithic or that may be built up of tiles, slabs, etc., laid in cement, and supporting a weatherproof and fireproof coating.

Another object of my invention is to so arrange the elements of the weather- and fireproof coating of a roof with relation to the gutter formed in the masonry foundation element thereof that said elements will extend in the direction of the flow of water in said gutter, whereby an unobstructed flow is assured and the possibility of water destroying joints between elements is avoided.

Another object is to so arrange weather- and fireproofing elements of a roof with relation to a masonry foundation element thereof having a gutter that a durable gutter covering will be formed, which will be connected to a weather- and fireproof covering of the water-shed of the roof in a manner to resist the action of the weather and allow for expansion of the elements and the roof.

Other and further objects and advantages will appear from the description taken in connection with the accompanying drawings forming a part of the specification and pointed out in the hereunto appended claim.

In the accompanying drawings,

Figure 1 is a perspective view of a portion of a roof having a gutter and provided with a weather- and fireproof cover embodying my invention, parts of the elements and asphalt layers of the covering being broken away;

Fig. 2 is a cross-section of the structure shown in Fig. 1.

In modern buildings it is highly desirable that all parts used in construction be as permanent and fireproof as possible, and the roof is usually made of masonry which may be formed of concrete or of tiles, etc., laid in cement. The drawings illustrate a roof 1 made of concrete, having a gutter 2 formed by a horizontal section 3 of the roof and an upwardly-extending wall section 4. The roof foundation being of masonry, it is necessary that a priming or filling material 5 be applied thereto to enter into the pores and thereby attach itself to the foundation and, at the same time, provide a surface to which weatherproof material will adhere. On top of the filling or priming material 5, preferably after it has dried or hardened, is placed a comparatively heavy coat 6 of asphalt which has been heated so that it may be spread with a mop or in some well-known manner. The heat of this coating when it is applied causes it to adhere to the coating 5, which may be asphalt or any material which will serve the purposes hereinabove stated. These two coatings 5 and 6 cover the water-shed of the roof, as well as the surface of the gutter, including the wall forming a part thereof. Longitudinally of the gutter there is now laid upon the hot coating 6 a strip 7 of asphalt-saturated asbestos felt. This is rolled into the coating 5 while it is still hot, so that it becomes firmly attached thereto. The surface of this layer is then mopped with a coating 8 of asphalt, which is heated up so that it may be spread by a mop. On top of this coating 8 there is applied a strip 9 of asphalt-saturated asbestos felt, which is wider than the strip 7, and which fits into the gutter, covering the wall and the bottom thereof, and it is rolled down onto the layer 8 of asphalt before that asphalt is cooled, so that this layer of felt is firmly attached to the roof. This layer is then mopped with a coating of asphalt 10, and, while this coating is still hot, another layer 11 of felt is placed on it, which layer is wider than the layer 9. This layer 11 is in turn mopped with a coating of asphalt 12, and a layer 13 of felt is rolled into it while it is still hot. The surface of this layer is then mopped with a final layer of asphalt 13'. The layer 13 of felt is preferably the widest of those forming the covering of the gutter. Additional longitudi-

nal strips 14, 15, 16 and 17 are placed upon the roof, so as to build up thereon a covering, composed of longitudinal strips positioned over one another so that joints are broken, which will extend up onto the sloping portion of the roof to the same level as the top of the wall 4 which forms one side of the gutter. A gutter is thus formed which has a lining composed of longitudinal strips, the strips extending up on both sides to the same level, so that, no matter how full the gutter may be, the water therein will always be flowing over strips extending in the direction of flow, and which will have no lateral joints across which water flows, or, if they do have joints, the joints will be so few that they will be negligible.

It will be seen that a gutter is provided, therefore, which has positively no obstruction to the flow of water in the direction of its length, and which comprises many plies of asphalt-saturated asbestos felt between which and above and below which there are layers of asphalt.

The layers 14, 15, 16 and 17 are laid so that they overlap the layers 9, 11 and 13 and overlap one another so that at least four layers of asbestos felt are provided at any point in the gutter. Between and on top of the layers 14, 15, 16 and 17 of felt are layers 18 of asphalt, which have been applied with a mop while hot, and to which the felt is applied and rolled in as described in connection with the application of layers 7, 9, 11 and 13.

The water-shed of the roof is covered by layers of felt which extend from the upper edge of the gutter to the ridge of the roof. The lower layer 19 is applied to the layer 40 of asphalt 6 while it is hot and rolled into said layer of asphalt. On top of the layer of felt 19 are positioned the layers of felt 20 and 21, having between and on top of them the layers of asphalt 23, which layers are applied while the asphalt is hot and into which layers the felt is rolled as it is applied.

It will be seen that a roof has been described which has a gutter with a lining which has absolutely no obstruction to the flow of water therein, together with a cov-

ering for the roof the layers or plies of which extend from the gutter to the ridge in a manner which has been found by experience to be the most practical in roof 65 covering.

On top of the wall 4 and extending down into the gutter is placed the usual cap 25 to protect the edges of the layers 7, 9 and 11 from the action of the weather. 60

While a specific structure of a roof embodying the invention herein disclosed has been described, it is not intended that this invention shall be restricted to the specific features so described, but it is intended that the invention shall be defined by the claim hereunto appended.

What I claim and desire to secure by Letters Patent of the United States is the following:—

In a roof, a masonry foundation comprising a sloping water-shed portion and a portion extending upwardly therefrom and forming a gutter therewith and a covering for said foundation comprising a plurality of superimposed strips or plies of waterproofed fibrous material laid longitudinally of said gutter and extending across said gutter from the upper edge thereof, each successive strip or ply from the lower ply or strip upwardly being of greater width than the preceding strip or ply, a plurality of additional superimposed strips or plies of waterproofed fibrous material laid longitudinally of said gutter and overlapping said first-named strips or plies, each successive ply or strip from the lower ply or strip upwardly having less overlap, said last-named strips or plies extending onto said water-shed portion and a plurality of strips or plies of waterproofed fibrous material, extending over said water-shed portion in the direction of slope thereof, all of said strips or plies being laid in adhesive material and arranged to form a continuous covering for said roof having a gutter with an unobstructed and substantially uninterrupted surface extending in the direction of flow of water therein.

In testimony whereof, I have signed my name to this specification.

FRANK L. FOSTER.
